UNITED STATES PATENT OFFICE.

NATHAN C. MERRILL, OF CHICAGO, ILLINOIS.

LEG-MOUNTING FOR UPTILTING BEDS.

972,462.

Specification of Letters Patent. Patented Oct. 11, 1910.

Application filed October 28, 1909. Serial No. 525,184.

To all whom it may concern:

Be it known that I, NATHAN C. MERRILL, a citizen of the United States, residing at Chicago, in the county of Cook and State of Illinois, have invented a certain new and useful Improvement in Leg-Mountings for Uptilting Beds, of which the following is a specification.

This invention relates to up tilting beds commonly called folding beds and primarily to those mounted upon pivotal doors for swinging the bed from a room into a closet or other recess adapted to conceal the bed during the day or when otherwise not in use.

The object of the invention is to prevent the leg from breaking when the bed is in usable or working position in the room due to the necessary lateral or side thrust of a bed mounted on a door centrally pivoted.

The invention consists in a keeper or retaining device which is engaged by the leg of the bed as it swings down to vertical or usable position, said keeper being so located that it takes up side strain upon the bed leg and thereby prevents the leg being snapped off at the pivot.

The invention also consists in other details of construction as will be more fully described and claimed as the specification proceeds.

Referring to the drawings, Figure 1 is a front view of a door panel having a folding bed attached thereto, the bed being in lowered or usable position. Fig. 2 is a detail view of a corner adjacent to the foot of the bed showing the position which the parts assume when the bed is in an up tilted position. Fig. 3 is a view of the same parts when the bed is lowered and is supported by the leg in usable position. Fig. 4 is a detail plan view taken on the line 4-4, Fig. 3.

Fig. 5 is a detail sectional side view of the pivotal connection for the leg upon the bed.

Again referring to the drawings, the numerals 8 indicate the door frame in which the door proper 10 is mounted upon vertical pivots 12 and 14 so as to swing thereon at least 180 degrees. On the front of this door 10 is mounted the folding bed 15 of any desired construction pivoted upon pivots not shown in detail, adjacent to the door and be adapted to swing up against the door and be rotated by the door through the door opening into the room not seen behind the door panel 10. As is well known in the art, this

bed is provided with pivotal mountings 16 carrying on each side of the bed depending supporting legs 18 attached near the foot board 20 and side rail 22 of the bed adapted, 60 in the position of Fig. 2, to hang as shown parallel to the side rail and out of the way, and adapted when the same parts have been lowered until the bed is in usable position, as shown in Fig. 3, to swing through 90 degrees to the position shown in that figure thereby supporting the foot end of the bed upon the floor. If only the parts thus far described are used and the parts are swung to the position of Fig. 3, as just described, and then the bed is given even a slight rotary motion upon the pivots 12 the result is very frequently the snapping off of the legs 18 at or near the pivot 16 or the breaking of the pivots themselves. In order to avoid this difficulty a clip or keeper 24 is provided adjacent to each leg 18 when it is in the position of Fig. 3 which engages that leg in such a way as to do away in a large measure, if not completely, with the side strain upon 75 the pivot 16. The shape of the leg and keeper is such that when the leg is perpendicular in usable position, the leg is held firm, with no side motion, and as the weight of the bed comes upon the leg, the pivot 16 80 slides down in the slotted hole 26 in the leg, which forces the upper or tapering end 28 of the leg into a corresponding taper 30 on the head 32, which binds the leg so it is perfectly rigid in every direction, and cannot be 85 turned until the bed is raised, when the weight of the leg causes it to drop into a loose position.

Having thus described my invention what I claim as new, and desire to secure by Letters Patent is:—

1. In combination, a panel swinging in a vertical plane, a bed hinged thereto, a leg pivoted at a fixed point to the bed near the foot thereof and a keeper on the frame at a 90 substantial distance from the pivot of the leg adapted to engage the leg when the bed is lowered to brace the same against the strain caused by swinging movement of the panel.

2. In combination with an uptilting bed, a leg pivoted near the foot thereof adapted to support the bed when in usable position, a clip or keeper attached to the frame of the bed adjacent to the position of the leg when the bed is in usable position, at a distance 100 from the pivot of the leg, adapted to have

the leg pass between it and the frame of the bed and in substantial contact with both for the purposes set forth.

3. In combination, a swinging panel, a bed hinged thereto, a leg pivoted to the bed near the foot thereof, the pivot of said connection traveling in a slot in the adjacent member perpendicular to the bed, means in said pivot and slot connection adapted to automatically lock the bed and leg in contact with each other when the bed is in lowered

position, and a keeper adapted to engage the leg when the bed is lowered to brace the same against the strain caused by swinging movement of the panel.

15

In witness whereof, I have hereunto subscribed my name in the presence of two witnesses.

NATHAN C. MERRILL.
